WIRELESS AERIAL SYSTEM

Edward Cecil Cork, Ealing, London, and Joseph Lade Pawsey, Hillingdon, England, assignors to Electric & Musical Industries Limited, Middlesex, England, a company of Great Britain

Application March 15, 1937, Serial No. 130,880
In Great Britain March 17, 1936

5 Claims. (Cl. 250—33)

The present invention relates to wireless aerial systems and more particularly to dipole aerials for operation at a relatively short wavelength.

In the design of a short wave aerial for handling a carrier wave and wide side bands such as are required for television purposes, it is necessary to reduce the variation of reactance with frequency as much as possible. By using elements consisting of cylinders of large diameter or wide strips, the variation of reactance can be substantially reduced. In many cases, and particularly in cases where an auxiliary conductor of the type described in the specification of United States patent to W. S. Percival, et al., #2,127,083, granted August 16, 1938, is associated with the aerial end of a concentric feeder, a large amount of reactance may be introduced in the connections between the aerial elements and the feeder. This reactance may be considerably in excess of that of the aerial elements, in which case the frequency characteristic of the aerial will be adversely affected.

It is an object of the present invention to provide a new or improved arrangement for connecting a dipole aerial to a concentric feeder.

According to the present invention, in an aerial system including a dipole aerial, a feeder and an auxiliary conductor which serves to prevent the flow of current at the frequency to be transmitted or received along the sheath of the feeder, the surfaces of the dipole elements being large in order to reduce variations in reactance of the aerial with variation in frequency, reactance introduced due to the connections between the dipole elements and the feeder or the auxiliary conductor or both, is reduced by disposing the open ends of the feeder and auxiliary conductor so that the connection of the central conductor of the feeder to the auxiliary conductor is as short as possible consistent with maintenance of adequate insulation between the ends of the auxiliary conductor and sheath. The dipole elements may be cylindrical and in such a case their adjacent ends are formed as truncated cones connected to the opposed ends of the sheath and auxiliary conductor. The ends of the feeder and auxiliary conductor connected to the dipole elements may be chamfered in order that the dipole elements may be disposed substantially coaxially. In a modified construction according to the invention, the adjacent ends of the dipole elements are each connected to conducting surfaces, the width of which is substantially the same as the width of the dipole elements, one of said conducting surfaces being connected to the end of the

sheath of said feeder, while the other is connected to the end of said auxiliary conductor. The auxiliary conductor used in systems operating in accordance with the invention may operate in the manner set forth in the above mentioned patent to W. S. Percival et al. 5

In order that the invention may be more clearly understood and readily carried into effect, two methods of connecting a dipole aerial to a feeder in accordance with the invention will now be 10 described by way of example with reference to the accompanying drawing in which,

Figure 1 shows diagrammatically in perspective a dipole aerial and concentric feeder connected in accordance with the invention, and 15

Figures 2 and 3 show an alternative form of construction.

Referring to Figure 1 of the drawing, a dipole aerial comprises two hollow cylindrical members 1, 2 each provided at one end with a frusto-conical portion 3, 4. The diameter of the smaller end of each frusto-conical portion is about one third the diameter of the larger end and the vertical semi-angle of the cone is about 55°. The larger ends of the frusto-conical portions have 25 the same diameter as, and are attached to, the cylindrical members. The two members 1, 2 are shown arranged one above the other, the frusto-conical ends being adjacent one another and separated from one another by a distance slightly 30 greater than the diameter of the sheath of a concentric feeder 5 which is to be connected to the aerial. The feeder 5 extends in a straight line for only a short distance from the end A connected to the dipole element 1 and it is bent 35 at the point B through a right angle in a horizontal plane. Two further right angle bends are made at the points C and D, the portion DH being of indefinite length depending upon the position of the transmitter. The points A, B, C, 40 D and H in the feeder all lie in a horizontal plane. The distance AB is equal to the distance CD and the length ABCD is arranged to be approximately 45 equal to one quarter of the operating wavelength.

An auxiliary conductor 6 which also has a 50 length approximately one quarter of the operating wavelength, and is of the same external diameter as the sheath of the feeder, is bent through a right-angle at points E and F and is connected at one end to the sheath of the feeder at D. It is arranged that GF=DE=DC=BA and that 55 FE=BC. Thus, B, C, E and F lie at the corners of a rectangle. The central conductor 7 of the feeder projects beyond the end of the sheath and 55

is connected to the end of the auxiliary conductor 6.

The spacing between the end G of the auxiliary conductor and the end A of the sheath of the feeder, is made as small as possible in order to keep the reactance of the connections to the members of the aerial as small as possible, but must be sufficiently great to prevent sparking.

In one particular case the variation of aerial reactance with a certain change of frequency was 5 ohms due to the reactance of the aerial itself, and the increase when connected to the feeder due to the reactance of the necessary connections was found to be small compared with 5 ohms. It will be seen that a system of this type is symmetrical about the vertical plane through H, D and A and also about the plane of the feeder.

In a modification of the arrangement described with reference to Fig. 1 of the drawings, the feeder is bent at B but, instead of being bent at C and D, extends away from the aerial in a straight line BCH. The auxiliary conductor is bent as before at E and F and extends to and is connected to the sheath of the feeder at C. The lengths ABC and GFEC require to be slightly different from the value of these lengths in the previously described arrangement.

The form of connection shown in Figure 2 differs from that shown in Figure 1 in that the dipole elements are enabled to be arranged coaxially one above the other by chamfering the ends of the feeder and auxiliary conductor respectively. In other respects the details of Figure 2 are as shown in Figure 1. It will be seen that the construction shown in Figure 2 permits the ends of the feeder and auxiliary conductor to be brought close together, thereby keeping to a low value any reactance introduced by the connection between the central conductor of the feeder and the auxiliary conductor.

Referring to Figure 3 of the drawing, the connection between a concentric feeder provided with an auxiliary conductor and a dipole aerial is shown effected by means of a length of open line. The aerial comprises two cylindrical members 1, 2 mounted one above the other and coaxially with one another, their adjacent ends being close together and each having a wide copper strip 8, 9 attached thereto. The strips may have a width equal to the diameter of the cylinders, for example, one or two feet. The strips extend, parallel with one another, horizontally away from the aerial and have their other ends connected respectively to the sheath of the feeder 5 and to the end of the auxiliary conductor 6 to which the central conductor 7 is also connected.

The auxiliary conductor 6 is of the same external dimension as the sheath of the feeder and has a length approximately equal to one quarter of the operating wavelength. It is disposed substantially parallel to the feeder and the end not connected to the dipole element 2 is connected to the sheath of the feeder.

The two strips form a line of low characteristic impedance between the feeder and the aerial. The distance between the strips is preferably just sufficient to prevent sparking and may be of the order of 1 inch.

Arrangements according to the present invention are of particular use as transmitting aerials but they may also be used for reception. It will be understood that although particular shapes of dipole elements have been described, any desired

practical shape presenting a large surface may be used.

We claim:

1. An aerial system comprising a dipole aerial the elements of which have a large surface area, a feeder for said aerial including a conductor and a conducting sheath surrounding said conductor, an auxiliary conductor associated with said sheath for preventing currents of the operating frequency from flowing over the outer surface of said sheath, said auxiliary conductor being arranged for the greatest portion of its length parallel to said sheath and having a length substantially an odd integral multiple of a quarter of the wave length at which the system is arranged to operate, one end of said auxiliary conductor being connected to said first mentioned conductor and positioned closely adjacent the end of said sheath and opposed thereto, the other end being directly connected to the outer surface of said sheath, the adjoining ends of said dipole elements being connected to the opposed ends of said sheath and said auxiliary conductor.

2. An aerial system comprising a dipole aerial the elements of which comprise cylinders of large diameter to reduce variations in reactance of the aerial with variation in frequency, a feeder for said aerial including a conductor and a conducting sheath surrounding said conductor, an auxiliary conductor associated with said sheath for preventing currents of the operating frequency from flowing over the outer surface of said sheath, said auxiliary conductor being arranged for the greatest portion of its length parallel to said sheath and having a length substantially an odd integral multiple of a quarter of the wave length at which the system is arranged to operate, one end of said auxiliary conductor being directly connected to the outer surface of said sheath, the other end of said auxiliary conductor being positioned closely adjacent the end of said sheath and opposed thereto, said end being connected to said first mentioned conductor, the adjacent ends of said dipole elements being connected to opposed ends of said sheath and said auxiliary conductor, said adjacent ends being formed as truncated cones whereby the reactance introduced due to the connections is reduced.

3. An aerial system comprising a dipole aerial the elements of which comprise cylinders of large diameter to reduce variations in reactance of the aerial with variation in frequency, each of said cylinders having a length equal to one-quarter of the length of the operating wave, a feeder for said aerial including a conductor and a conducting sheath surrounding said conductor, an auxiliary conductor associated with said sheath for preventing currents of the operating frequency from flowing over the outer surface of said sheath, said auxiliary conductor being arranged for the greatest portion of its length parallel to said sheath and having a length substantially an odd integral multiple of a quarter of the wave length at which the system is arranged to operate, one end of said auxiliary conductor being directly connected to the outer surface of said sheath, the other end of said auxiliary conductor being positioned adjacent the end of said sheath and connected to said first mentioned conductor and means for coupling said feeder to the elements of said dipole comprising a pair of closely spaced parallel conducting plates, the widths of which are substantially the same as the width of the dipole elements, one of said plates being connected to the end of said sheath and the other to the end of said auxiliary conductor said

pair of plates forming a low impedance connecting line between said feeder and said aerial.

4. An aerial system comprising a half wave dipole aerial the elements of which have a large surface area, a feeder for said aerial including a conductor and a conducting sheath surrounding said conductor, an auxiliary conductor associated with said sheath for preventing currents of the operating frequency from flowing over the outer surface of said sheath, said auxiliary conductor being arranged for the greatest portion of its length parallel to said sheath and having a length substantially an odd integral multiple of a quarter of the wave length at which the system is arranged to operate, one end of said auxiliary conductor being connected to said first mentioned conductor and positioned closely adjacent the end of said sheath and in opposed relationship thereto, the other end being directly connected to the outer surface of said sheath, the adjoining ends of said dipole elements being connected to the opposed ends of said sheath and said auxiliary conductor, the opposed ends of said sheath and auxiliary conductor being chamfered whereby said dipole aerial elements may be coaxially arranged.

5. An aerial system comprising a half wave dipole aerial the elements of which comprise cylinders of large diameter to reduce variations in

reactance of the aerial with variation in frequency, a feeder for said aerial including a conductor and a conducting sheath surrounding said conductor, an auxiliary conductor associated with said sheath for preventing currents of the operating frequency from flowing over the outer surface of said sheath, said auxiliary conductor being arranged for the greatest portion of its length parallel to said sheath and having a length substantially an odd integral multiple of a quarter of the wave length at which the system is arranged to operate, one end of said auxiliary conductor being directly connected to the outer surface of said sheath, the other end of said auxiliary conductor being positioned closely adjacent the end of said sheath and opposed thereto, said end being connected to said first mentioned conductor, the adjacent ends of said dipole elements being connected to opposed ends of said sheath and said auxiliary conductor, said adjacent ends being formed as truncated cones whereby the reactance introduced due to the connections is reduced, the opposed ends of said sheath and auxiliary conductor being chamfered whereby said dipole aerial elements may be coaxially arranged.
